Primary Examiner — Melanie H Tung

(57) **CLAIM**

The ornamental design for a display screen of a computing device with a computer-generated application catalog interface, as shown and described.

DESCRIPTION

FIG. 1 is a front view of a display screen of a computing device with a computer-generated application catalog interface; and,

FIG. 2 is front view of a second embodiment thereof. The broken lines shown in the drawings are for the purpose of illustrating a display screen of a computing device, text, and other images, and form no part of the claimed design.
